TONGUE PROTECTOR METHOD

Andrew S. Hartanov and Carl L. Lohner, Chicago,
Ill., assignors to Industrial Patents Corpora-
tion, Chicago, Ill., a corporation of Delaware

Application March 29, 1937, Serial No. 133,728

2 Claims. (Cl. 17—45)

This invention relates to a method of protecting the tongue of a carcass during processing.

One of the objects of the invention resides in a method of protecting a hog tongue from the teeth and from the dehairing beaters during dehairing of the carcass.

Other objects of the invention will be apparent from the description and claims which follow.

The accompanying drawing, by way of illustration but without limitation, exemplifies means which may be employed in the practice of the method of the present invention.

Figure 1 is a plan view showing one device which may be employed in the method of the present application.

Figure 2 is a side view showing the manner in which the device is employed in holding a hog tongue.

Figure 3 is an end view of the device shown in Figure 1.

Figure 4 is a plan view showing the modified form of the device shown in Figure 1.

Figure 5 is a side view showing the manner in which the modification shown in Figure 4 may be employed in holding a hog tongue.

Figure 6 is an end view of the device shown in Figure 4.

The device illustrated in Figures 1, 2, and 3 is preferably prepared of spring wire, provided with a closed loop 1 at one end for insertion in the hog's throat, and provided with means for holding the tongue protector in the hog's mouth. Closed loop 1 comprises sides 2 and 3, apex 4, and shoulders 5 and 6 merging respectively into resilient side arms 7 and 8 bent at 9 and 10 respectively to form an end guard.

Section 11 of the end guard is adapted to fit over the top surface of a folded tongue, and section 12 is adapted to fit on the under side of the tongue. Section 12 is provided with a narrow slit 13 for grasping a portion of the frenum linguae.

The forward end of the tongue abuts against the curved end portion of the protector, preventing the tongue from unfolding after the protector is in position. The loop 1 after insertion

into the hog's throat retains the protector in position and the slit 13 keeps the protector in place against lateral displacement.

The manner of engaging the tongue will be apparent from Figure 2, in which the tongue 14 is shown having the tip 15 folded back upon itself, a portion of the frenum linguae 16 being shown held by slit 13.

In the modification of the tongue protector of the present invention shown in Figures 4, 5, and 6, the guard 17 which serves to protect the tongue is prepared from sheet metal, preferably stainless steel. Slit 18 is provided in guard 17 to engage the frenum linguae. Flanges 19 are provided on each side to further prevent lateral movement relative to the tongue and to reduce the possibility of injury to the tongue from teeth in the back section of the hog's mouth.

It will be noted that the tongue protector of the present invention does not encircle or envelop the tongue and that the guard section of the protector is provided with means for securing the protector to the tongue and preventing lateral movement of the protector relative to the tongue.

In practicing the method of the present invention, the tip of the tongue is folded back upon itself and is thereby held by the protector in the back portion of the mouth cavity, where there is sufficient room to accommodate the tongue and the protector and where the likelihood of injury is minimized.

We claim:

1. The method of protecting a carcass tongue from injury which comprises folding the tongue back in the carcass mouth and maintaining the tongue in position in the back of the mouth cavity.

2. The method of protecting a carcass tongue from injury which comprises folding the tip of the tongue back against the body of the tongue in the carcass mouth and maintaining the tongue in folded position in the mouth cavity.

ANDREW S. HARTANOV. 45
CARL L. LOHNER.
